ALEXANDER J. SOCIA AND JOSEPH P. DALY, OF SYRACUSE, NEW YORK, ASSIGNEES,
BY MESNE ASSIGNMENTS, TO THE PROSPERITY COMPANY, INC., A CORPORATION OF
NEW YORK.

MECHANISM FOR PRESSING MACHINES HAVING START AND STOP MOTORS.

Application filed September 4, 1924. Serial No. 735,822.

This invention relates to pressing machines as garment and laundry pressing machines having an actuating mechanism including a start and stop motor and a toggle for transmitting the movement of the motor to the movable element of the press and has for its object a particularly simple motion transmitting mechanism for actuating the toggle and particularly for starting the breaking of the toggle when the motor is starting and effecting the final straightening of the toggle at the time the motor is about to stop, whereby a change or reduction in leverage ratio occurs so that the final heavy pressure is produced and also the initial opening of the press while under such heavy pressure, without overloading the motor or, in other words, so that the load on the motor is substantially even throughout the intermittent operation of the motor.

The invention consists in the novel features and in the combinations and constructions hereinafter set forth and claimed and described.

In describing this invention, reference is had to the accompanying drawings in which like characters designate corresponding parts in all the views.

Figure 1 is a side elevation of one form of pressing machine embodying our invention.

Figure 2 is a fragmentary elevation of the motion transmitting means between the cranks and the toggle, the toggle being shown in straightened or final pressure position.

Figure 3 is a view similar to Figure 2 showing the toggle in its folded position and the links in their position assumed when the toggle is folded.

Figure 4 is a sectional view on line 4—4, Figure 2.

Figure 5 is a fragmentary detail view of the rear end of the link connected to the longer crank.

Figure 6 is a face view of the means for guiding the sections of the link connected to the shorter crank into operative position.

This pressing machine comprises generally cooperating pressing elements, one of which

is movable toward and from the other, mechanism for actuating the movable element including an intermittently rotatable shaft, motion transmitting means between the shaft and the movable element usually including a toggle, connections between the shaft and the toggle to move the toggle from folded to nearly straightened position and from nearly straightened position to folded position and additional connections for finally straightening the toggle and initially breaking the toggle and driving means for intermittently actuating the shaft.

The machine here illustrated is a conventional type of pressing machine including a stationary lower buck 1 and a press head 2 movable toward and from the buck 1, the buck 1 being mounted upon a suitable frame 3 and the head 2 being carried on the forward arm of the vertically movable yoke or lever 4 pivoted at 5 between its ends to a standard 6 rising from the frame.

7 designates the intermittently rotatable shaft which makes a half revolution during each intermittent operation. Heretofore, this shaft has had a single rotary eccentric or crank thereon and this crank has been connected by a single connecting rod to the joint of a toggle, so that a half revolution in one direction unfolds the toggle and a half revolution in the other direction straightens the toggle and applies pressure to the head 2. The toggle links in the machines heretofore used are substantially the same as that shown herein and includes links 8 and 9 pivoted together at 10, the link 8 being pivoted at 11 to the rear arm of the yoke 4 and the link 9 being pivoted to the frame 12. The link 8 includes a suitable compression spring 13, but as the construction of the toggle in itself forms no part of this invention, further description is thought to be unnecessary.

The shaft is actuated from an intermittently operable electric motor 14, the armature shaft 15 of which is connected to a shaft 16 which in turn is connected to the shaft 7 through suitable worm gearing located within the housing 17.

The starting of the motor is manually controlled through a suitable tumbler switch located within a housing 18 and the stopping through an automatic controller or a change 70
over switch located within the housing 20 and including a part rotatable with the shaft 7. Commercial forms of this automatic controller for tumbler switch as embodied in commercial pressing machines are shown in
10 the Andree Patent No. 1,379,601, May 24, 1921, and Benjamin and Carroll Patent No. 1,489,227, April 1, 1924.

The construction of the tumbler switch and controller and the operation of the machine 80
15 by such tumbler switch and controller forms no part of our invention and as the same is shown in patent to Andree, No. 1,397,601, May 24, 1921, further description is thought to be unnecessary.

With a stop and start motor and crank, an 90
excessive load is thrown on the motor during the starting and stopping to obtain and release the final heavy pressure, and the crank and the connecting rod must stop in a straight 95
25 line. The moving of the crank and connecting rod into a straight or dead center line thrusts a sudden load on the motor and on account of this sudden load, the crank stops short of the dead center line and manual trip 100
30 release means are resorted to to initially release the pressure on the toggle before the motor can be started to effect the opening of the press.

This invention relates to connections be- 105
35 tween the shaft 7 and the toggle whereby the toggle is finally straightened and initially broken by varying or reducing the leverage ratio between the motor and the press head. This reducing of the load on the motor and at 110
40 the same time effecting the maximum pressure on the head 2 is effected by providing the shaft 7 with two cranks having different throws, the cranks being preferably arranged in the same radial line, a connecting rod or 115
45 link connecting the crank of longer throw with the toggle by a lost motion connection and a link connecting the crank of shorter throw and the toggle and operating to take up the lost motion in the first mentioned con- 120
50 nection rod and straighten the toggle from a nearly straightened position effected by the first mentioned connecting rod and to take up the lost motion in the opposite direction to initially break the toggle. In other words, 125
55 the cranks come in effective action successively.

The term cranks is used merely for convenience and it will be understood that any form of rotary eccentric means may be used. Also 130
60 it will be understood that the reduction in the leverage ratio brought about by two cranks may be used with motion transmitting means other than a toggle.

21 designates the shorter crank and 22 the 135
65 longer crank, these having crank pins 23 and

24, (Figure 4). The two pins 23 and 24 are connected by a link 24^a, rigid with both of said pins, so that the entire structure 21, 22, 23, 24 and 24^a is a unitary crank with two crank pins of different radii. 70

25 is a connecting rod or link between the longer crank 22 and the toggle, this rod 25 being mounted on the crank pin 24 at one end and connected to the joint 10 of the toggle at its other end by a lost motion connection, the link 25 having a short lengthwise slot 26 at its rear end for receiving the pivot pin 10. 75

The link connecting the shorter crank 21 and the toggle comprises sections out of operative relation to each other when the toggle is folded as shown in Figure 3 and movable into abutting or thrusting relation with each other and with the toggle and into pulling relation to the toggle when the toggle has been moved into a nearly straightened position by the link 25. In other words, the link between the shorter crank 21 and the toggle is shifted into operative position after the link 25 has done its work to nearly straighten the toggle and remains in such operative position to effect the initial breaking of the toggle when the circuit is again closed through the motor 14 to open the press. 80

As here illustrated, the link between the shorter crank 21 and the toggle comprises three sections 27, 28 and 29, the section 27 being mounted at one end on the crank pin 23 of the shorter crank 21 and extending rearwardly therefrom; and the section 28 being pivoted on the pivot pin 10 of the joint of the toggle and extending forwardly therefrom, the sections 27 and 28 having respectively shoulders 30 and 31 arranged to be brought into abutting relation as shown in Figure 2 during the closing of the press, so that as the 105 cranks approach the dead center line these shoulders come into abutting relation and the section 27 thrusting against the section 28 finally straightens the toggle and moves the joint 10 thereof from the front end of the slot 26 toward the rear end of the slot 26 of the link 25. 110

The section 29 is pivoted at 32 to the section 27 and normally extends upwardly and rearwardly and has a hook 33 at its rear end arranged to hook over the pivot 10 of the toggle when the toggle is in its straightened position, so that when the motor is energized to open the press, the hook 33 pulling on the pivot pin 10 initially breaks the toggle, this being permitted by the slot 26 in the lever 25. Thus the toggle is finally straightened and initially broken by the crank having a short throw or a crank having less leverage than the longer crank 22. These sections 27, 28 and 29 may for convenience be referred to as a push and pull section (27), a push section (28) and a pull section (29). The section 28 is moved from its position shown in Figure 3 to that shown in Figure 2 and vice-versa by 120

a link 34 pivoted at 35 to the front end of the link 28 and at 36 to one of the links of the toggle as the link 8, it being shown as being connected to one of the parts it connects by a lost motion connection and as here illustrated it is formed with a slot 38 for receiving the pin 36.

The sections 28 and 29 are connected together to move in synchronism by a suitable connection as a pin 39 on the section 28, which pin extends through a lengthwise slot 40 in the section 29. Also the sections 27 and 28 are guided into abutting relation and the section 27 held from undue displacement by a cam plate 41 suitably secured to the frame and having a cam slot 42 therein for receiving a follower on the section 27, this follower being usually at the end of the pivot pin 32. The section 27 is shown as bifurcated, and also the section 28 is bifurcated, and the section 29 extends between the bifurcations of the sections 27 and 28. The slot 42 in the cam plate 41 is formed with a dip or deflected portion near one end as seen in Figure 6. This deflected portion causes the section 27 or the shoulder 30 thereof to dip or to hook under the shoulder 38 of the section 29, as these sections 27 and 28 are coming into a straight line. The shoulder 31 overhangs the dip portion of the slot 42 and causes the shoulder 30 to dip under or to clear the overhanging part of the shoulder 31 as the links or sections 27 and 29 come into abutting relation.

In operation, assuming that the press is open and the toggle in its position shown in Figure 3, the operator throws the tumbler switch 18 by a suitable handle so that the current passes through the motor 14 and the motor starts actuating the shaft 7.

The motion is initially transmitted by the longer crank 22 through the link 25 to the toggle and moves the toggle nearly into the dead center line of the toggle. As the toggle approaches a straight line, the section 27 of the link connected to the shorter crank is brought into abutting relation with the section 28, so that a continued rotation of the shaft 7 moves the cranks into their dead center line with the connecting rod links and moves the toggle links 8, 9 into their dead center line thus applying final or heavy pressure by motion transmitted through the shorter crank.

When the cranks complete the half revolution, the controller switch within the casing 20 automatically breaks the circuit as in the Andree patent referred to.

Also as the link 28 comes into abutting relation with the link 27, the link 29 having the hook 33, is brought into a pulling relation with the joint 10 of the toggle, so that when the circuit is again closed through the motor by actuating the tumbler switch 18, the section 29 having the hook 33 is pulled

forwardly by the short crank and initially breaks the toggle. After the toggle is broken, the longer crank 22 through the connecting link 25 completes the opening operation.

What we claim is:—

1. In a pressing machine, the combination of cooperating pressing elements, one of which is movable toward and from the other, and mechanism for actuating the movable element including an intermittently rotatable shaft, motion transmitting means between the shaft and the movable element including a toggle, connections between the shaft and the toggle for moving the toggle toward and from nearly straightened position, and additional connections between the shaft and the toggle for finally straightening the toggle and initially breaking the toggle. 70

2. In a pressing machine, the combination of cooperating pressing elements, one of which is movable toward and from the other, and mechanism for actuating the movable element including an intermittently rotatable shaft and motion transmitting means between the shaft and the movable element including a toggle and two sets of connections between the shaft and the toggle for straightening and unfolding the toggle, one set operating to initially break the toggle. 85

3. In a pressing machine, the combination of cooperating pressing elements, one of which is movable toward and from the other, and mechanism for actuating the movable element including an intermittently rotatable shaft and motion transmitting means between the shaft and the movable element including a toggle and two sets of connections between the shaft and the toggle arranged to come successively into action, one set operating in advance of the second set to nearly straighten the toggle and the second set to finally straighten the toggle, and the second set being arranged to come into action in advance of the first set to initially break the toggle. 95

4. In a pressing machine, the combination of cooperating pressing elements, one of which is movable toward and from the other, mechanism for actuating the movable element including an intermittently rotatable shaft having a pair of cranks thereon, driving means to actuate the shaft one-half revolution during each intermittent operation, motion transmitting means between the cranks and the movable element including a toggle and connections between the cranks and the toggle, one connection including a link connecting one crank and the toggle by a lost motion connection and the other connection comprising means connected to the other crank and movable into connection with the toggle to take up the lost motion in one direction of said link and finally straighten the toggle during the closing movement of the press and to initially break the toggle and take up said lost motion in the other direc- 115

125

130

tion during the opening movement of the press.

5. In a pressing machine, the combination of cooperating pressing elements, one of which is movable toward and from the other, mechanism for actuating the movable element including an intermittently rotatable shaft having a pair of cranks thereon, said cranks extending in the same radial line and one being shorter than the other, driving means to actuate the shaft one-half revolution during each intermittent operation, motion transmitting means between the cranks and the movable element including a toggle and connections between the cranks and the toggle, one connection including a link connecting the longer crank and the toggle by a lost motion connection and the other connection comprising link means connected to the shorter crank and normally disconnected from the toggle and movable into effective connection with the toggle to take up the lost motion in one direction and finally straighten the toggle at the end of the closing movement of the press and to initially break the toggle and take up the lost motion in the other direction during the opening of the press.

6. In a pressing machine, the combination of cooperating pressing elements, one of which is movable toward and from the other, mechanism for actuating the movable element including an intermittently rotatable shaft having a pair of cranks thereon, said cranks extending in the same radial line and one being shorter than the other, driving means to actuate the shaft one-half revolution during each intermittent operation, motion transmitting means between the shaft and the movable element including a toggle and connections between the cranks and the toggle, one connection including a link connecting the longer crank and the toggle by a lost motion connection and the other connection comprising linkage means connected to the shorter crank and movable into connection with the toggle to finally straighten the toggle and take up the lost motion in one direction as the press closes and to initially break the toggle and take up the lost motion in the other direction during the initial part of the opening of the press, the cranks being arranged to be brought into a straight line with the link and link means when the toggle is straight.

7. In a pressing machine, the combination of cooperating pressing elements, one of which is movable toward and from the other, mechanism for actuating the movable element including an intermittently rotatable shaft having a pair of cranks arranged in the same radial line and the length of one being less than the other, driving means for actuating the shaft a half revolution during each intermittent operation, motion transmitting means between the shaft and the movable ele-

ment including a toggle, a link connecting the longer crank and the toggle by a lost motion connection, means connecting the shorter crank and the toggle comprising sections, one being mounted on the shorter crank and the other on the toggle, the sections being movable into abutting relation as the toggle approaches a straight line and means for effecting the movement of the sections into and out of abutting relation.

8. In a pressing machine, the combination of cooperating pressing elements, one of which is movable toward and from the other, mechanism for actuating the movable element, including an intermittently rotatable shaft, having a pair of cranks, one crank having a different throw than the other, driving means for actuating the shaft a half revolution during each intermittent operation, motion transmitting means between the crank and the movable element including a toggle, a link connecting the crank of longer throw and the toggle by a lost motion connection, and means connecting the crank of shorter throw and the toggle, said means including folding sections connected respectively to the toggle and the shorter crank to be moved thereby into and out of coacting relation.

9. In a pressing machine, the combination of cooperating pressing elements, one of which is movable toward and from the other, mechanism for actuating the movable element, including an intermittently rotatable shaft, having a pair of cranks, one crank having a different throw than the other, driving means for actuating the shaft a half revolution during each intermittent operation, motion transmitting means between the cranks and the movable element, including a toggle, a link connecting the crank of longer throw and the toggle by a lost motion connection, and means connecting the crank of shorter throw and the toggle, said means comprising folding sections, one being mounted on the shorter crank, a second section normally out of abutting relation with the first section, and movable into abutting relation with the first section to finally thrust the toggle into straightened position, and means for effecting the movement of the second section.

10. In a pressing machine, the combination of cooperating pressing elements, one of which is movable toward and from the other, mechanism for actuating the movable element including an intermittently rotatable shaft having a pair of cranks, one crank having a different throw than the other, driving means for actuating the shaft a half revolution during each intermittent operation, motion transmitting means between the cranks and the movable element including a toggle, a link connecting the crank of longer throw and the toggle by a lost motion connection, and means connecting the crank of shorter throw and the toggle, said means comprising folding

- sections, one being mounted on the shorter crank, a second section normally out of abutting relation with the first section, and movable into abutting relation with the first section to finally thrust the toggle into straightened position, a second link pivoted to the first section and normally arranged out of a straight line therewith, and out of engagement with the toggle and means for moving the second link into pulling relation with the toggle when the toggle is brought into a straight line to start the unfolding of the toggle, and means for effecting the movement of the first and second sections.
11. In a pressing machine, the combination of cooperating pressing elements, one of which is movable toward and from the other, mechanism for actuating the movable element, including an intermittently rotatable shaft having a pair of cranks, one crank having a different throw than the other, driving means for actuating the shaft a half revolution during each intermittent operation, motion transmitting means between the shaft and the movable element including a toggle, a link connecting the crank of the longer throw and the toggle by a lost motion connection, and means connecting the crank of shorter throw and the toggle, said means including folding sections connected respectively to the toggle and to the shorter crank and being normally out of effective motion transmitting relation and movable into effective motion transmitting relation with each other and with the toggle as the toggle is brought into nearly straightened position by the first link and the longer crank, and means for shifting the sections into and out of motion transmitting relation as the toggle straightens and after the toggle is initially broken.
12. In a pressing machine, the combination of cooperating pressing elements, one of which is movable toward and from the other, mechanism for actuating the movable element, including an intermittently rotatable shaft having a pair of cranks, one crank having a longer throw than the other, driving means for actuating the shaft a half revolution during each intermittent operation, motion transmitting means between the cranks of the movable element including a toggle, a link connecting the crank of the longer throw and the toggle by a lost motion connection, means connecting the shorter crank and the toggle including a push and pull section mounted on the shorter crank, a pull section pivoted to the first section and extending upwardly and rearwardly when the toggle is folded, a push section mounted on the joint of the toggle and normally extending upwardly and forwardly crosswise of the pull section, the push and the pull sections being connected by a pin and slot connection, a link connecting the push section and one of

the links of the toggle, and means for guiding the sections into coacting relation with each other and the toggle.

13. A pressing machine having a mechanism for actuating the movable pressing element including an intermittently rotatable shaft, driving means for the shaft including a start and stop motor and means including a manually operable part for controlling the starting of the motor and automatic means for controlling the stopping thereof; said intermittently rotatable shaft being provided with a pair of cranks having different throws, the cranks being arranged in the same radial line and one being longer than the other, motion transmitting means between the cranks and the movable pressing element including a toggle, a link connecting the longer crank and the toggle by a lost motion connection and means connecting the shorter crank and the toggle and arranged to effect the final straightening of the toggle and the initial opening of the toggle, the cranks being movable into a straight line with the link and said means when the shaft is at the end of each intermittent operation.

14. In a pressing machine, the combination of cooperating pressing elements, one of which is movable toward and from the other, and mechanism for actuating the movable element, including an intermittently rotatable shaft having a pair of cranks thereon, and motion transmitting means between the cranks and the movable element, movable into action successively, and driving means for actuating the shaft a one-half revolution during each operation, the cranks movable in substantially the same radial line, and one being longer than the other, and a movable part to which the motion of the cranks is transmitted, the motion transmitting means comprising a link mounted on one crank and connected to said part, a sectional link comprising a section mounted on the other crank and a second section shiftable into and out of engagement with the first section and said part, and means operated by the first link and the part actuated thereby for moving the sections into and out of coacting position.

15. In a pressing machine, the combination of cooperating pressing elements, one of which is movable toward and from the other, and mechanism for actuating the movable element, including an intermittently rotatable shaft having a pair of cranks thereon, and motion transmitting means between the cranks and the movable element, movable into action successively, and driving means for actuating the shaft a one-half revolution during each operation, the cranks being arranged in substantially the same radial line, and one being longer than the other, a movable part to which the motion of the cranks is transmitted, the motion transmitting means comprising a link mounted on one

crank and connected to said part, a sectional link comprising a section mounted on the other crank and a second section shiftable into and out of engagement with the first section and said part, and means operated by the first link and said part for moving the sections into and out of coacting position.

In testimony whereof, we have hereunto

signed our names at Syracuse, in the county of Onondaga, and State of New York, this 27th day of August, 1924, and at Syracuse, in the county of Onondaga, and in the State of New York, this 27th day of August, 1924, respectively.
